PUMP SYSTEM

Joseph A. Boyd, Pendergrass, Ga., assignor of
three-fourths to Coley B. Whelchel, Jefferson,
Ga.

Application September 22, 1941, Serial No. 411,920

4 Claims. (Cl. 230—216)

My invention relates to the generation of power, and has among its objects and advantages the provision of an improved section of driveway designed to utilize vehicles passing thereover for compressing air in a storage tank to perform useful work.

In the accompanying drawing:

Figure 1 is a plan view of a section of driveway incorporating my invention;

Figure 2 is a sectional view along the line 2—2 of Figure 1; and

Figure 3 is an enlarged sectional view along the line 3—3 of Figure 2.

In the embodiment selected for illustration, I make use of a pavement or driveway section 10 provided with closely spaced air compressing cups 12. These cups are preferably of circular formation when viewed according to Figure 1. In Figure 3 the cups 12 are inverted and provided with beads 14 about their perimeters, which beads are secured in flanges 16 about the perimeters of metallic plates 18 anchored in the pavement 20 at such depths as to bring the flanges 16 flush with the pavement surface 22. The cups 12 are preferably formed of rubber.

Each plate 18 is provided with a short tube 24 having communication with the air space 26 of its cup and provided with a valve seat 28. A pipe 30 is connected with the tube 24 and serves as an abutment for a compression spring 32 which urges a ball valve 34 against the seat 28. Each plate 18 is also provided with a second tube 36 connected with a pipe 38. Tube 36 has communication with the space 26 and is provided with a valve seat 40 normally engaged by a ball valve 42 urged thereagainst by a compression spring 44 having one end engaging the plate 18 and its other end engaging the ball valve. Pipe 38 constitutes an air inlet conduit for its respective cup 12 while the pipe 30 constitutes an air outlet conduit for the same cup.

In operation, the resilient material of the cup 12 and its specific formation cause the cup to assume the normal contour of Figure 3. Movement of the vehicle across the cup causes collapse thereof, which forces air in the space 26 past the ball valve 34 and into the outlet conduit 30. As pressure is removed from the cup 12, the cup returns to its normal position which causes air to reenter the cup past the ball valve 42. All the cups are identical in construction and operation, and each pipe 30 is connected with a cross pipe 46 having a branch pipe 48 communicating with an air storage tank 50. Each pipe 38 is connected with a cross pipe 52 having an air inlet branch

54. Thus the air compressed through the medium of the cups 12 is delivered to the storage tank 50, while air for refilling the cups is delivered thereto through the medium of the branch pipe 54, the cross pipe 52 and the pipes 38.

The cups 12 project above the pavement surface 22 so that the cups are fully collapsed when a vehicle wheel passes thereover. The normal contour of the cups is a gentle one and the resilient nature of the cups affords complete protection against injury to the vehicle wheels. The plates 18 and all the pipes 30 and 38 are effectively anchored in the pavement 20.

Without further elaboration, the foregoing will so fully illustrate my invention, that others may, by applying current knowledge, readily adapt the same for use under various conditions of service.

I claim:

1. The combination of an air storage tank, a resilient and compressible air chamber means inherently cupped and adapted to be anchored to a driveway structure, an air inlet conduit means for said air chamber lying beneath the vehicle supporting surface of the driveway and provided with an air inlet check valve means, and an air outlet conduit means placing the air chamber in communication with said air storage tank and provided with an air outlet check valve means, said air outlet check valve means lying beneath the vehicle supporting surface of the driveway, said air chamber means normally projecting above the face of the driveway structure and being collapsible by a vehicle passing thereover to deliver air trapped therein to said air storage tank.

2. The combination of an air storage tank, a resilient and compressible air chamber inherently cupped and adapted to be anchored to a driveway structure, an air inlet conduit for said air chamber provided with an air inlet check valve lying beneath the vehicle supporting surface of the driveway structure, and an air outlet conduit placing the air chamber in communication with said air storage tank and provided with an air outlet check valve lying beneath the vehicle supporting surface of the driveway structure, said air chamber normally projecting above the face of the driveway structure and being collapsible by a vehicle passing thereover to deliver air trapped therein to said air storage tank.

3. The combination of an air storage tank, a series of closely spaced resilient and compressible air chambers inherently cupped and adapted to be anchored open faces down to a driveway structure, each compressible air chamber being pro-

vided with an air inlet conduit provided with an air inlet check valve lying beneath the vehicle supporting surface of the driveway structure, and an air outlet conduit for each compressible air chamber communicating with said air storage tank and provided with an air outlet check valve lying beneath the vehicle supporting surface of the driveway structure, said air chambers normally projecting above the face of the driveway structure and being compressed by a vehicle passing thereover to deliver the air trapped therein to said air storage tank.

4. The combination of a pavement, flanged plates anchored in said pavement, compressible dome-shaped cups having their perimeters se-

cured to the respective plates by the flanges thereof, said cups being inherently dome-shaped, an air inlet check valve means communicating with each cup and attached to the plate thereof, 5 an air outlet check valve means communicating with each cup and attached to the plate thereof, a storage tank, conduits connecting each air outlet check valve means with said storage tank, and conduits connected with said air inlet check valve means and communicating with the atmosphere, said cups normally projecting above the face of said pavement to be collapsed by a vehicle passing thereover for delivering air trapped therein to said storage tank.

JOSEPH A. BOYD.
